STOCKING

Harry E. Katzenmoyer, Hendersonville, N. C., assignor, by mesne assignments, to Chipman Knitting Mills, Easton, Pa., a corporation of Pennsylvania

Application February 7, 1941, Serial No. 377,810

3 Claims. (Cl. 66—184)

This invention relates to stockings and, more particularly, to stockings of the type formed from continuously knit flat fashioned blanks in which the upper halves of the heel portions are progressively widened, and the lower halves of said heel portions are progressively narrowed for emergence into the foot.

One object of this invention is to enable the formation of run-proof selvages along the widened upper halves of the heel portions without necessitating incidental loop transfers; such objective being attained, as hereinafter more fully disclosed, through the use of plural yarns of the same kind and count in alternation and in repeating sequence during the knitting of said heel portions, and merely increasing the traverse of the carriers for the addition of end loops in the widened courses.

Another object of this invention is to strengthen the selvages at the upper heel halves which is realized in practice, as also hereinafter more fully explained, by carrying the splicing yarns clear to the selvage loops for incorporation into them.

Another object of this invention is to provide a stocking having the above characteristics wherein the rough surface of the fabric and the ridge of the rear seam are at the inside of the stocking.

One embodiment of this invention is typified in the accompanying two sheets of illustrative drawings, wherein like characters of reference are applied to corresponding parts in all the views; while the concluding claims more particularly recite the features of novelty over the prior art.

In the drawings:

Fig. 1 is a side view of a full-fashioned stocking conveniently embodying the present improvements, with a fragmentary portion broken out to show the rough or wale in-side surface of the fabric.

Fig. 2 is a broken view illustrative of the manner in which the full-fashioned foot is formed in continuation of the stocking leg; and,

Fig. 3 is a fragmentary view showing the texture along one side edge of the widened heel portion of the stocking leg blank.

From Figs. 1 and 2 it will be understood the stocking 1 is knitted as a continuous blank according to the ringless method from a plurality of main or body yarns (in this instance three) of the same kind and count used in alternation and in repeating sequence, starting with the welt 2 and ending with the toe tip 3; while the leg 4 is shaped, in accordance with conventional practice,

down to a substantially uniform width ankle portion 5.

In accordance with this invention, and beginning at the course 6, the heel portions 7 are shaped by widening 8 with incidental formation of selvages 9, Fig. 3; followed by maintenance of the width of the fabric uniform for a few courses indicated at 10 in Fig. 2; whereupon said heel portions are further shaped by narrowing 11, followed by completion of the foot 12 to the toe tip 3 in any approved manner.

Referring now more particularly to Fig. 3, which shows how the widened heel portions 7 of the stocking 1 are formed after knitting of the ankle portion 5 to the courses 6, successive widening loop courses 13, 14, and 15, are knit of plural body yarns 16, 17 and 18 in repeating sequence and inclusion of a reinforcing yarn 19, incidental to addition of plural end loops 20, with attendant formation of interlocking selavage loops 21 which are proof against raveling.

Immediately after the running in of the uniform width ankle portion 5, the lower halves 11 of the heel projections 7 are shaped for emergence into the foot by inwardly transferring a constant number of end loops 20 periodically at opposite edges of the blank with incidental formation of symmetrically arranged lines of fashioning marks at 11'. After completion of the blank as explained, I fold the blank longitudinally so that the rough or wale face of the fabric is at the outside as indicated by a conventional legend notation in Fig. 1, and then seam up the selvages 21. Finally the stocking 1 is reversed with the result that the rough or wale face of the fabric and the ridge of the seam are at the inside. These last steps are accomplished in substantially the same way as disclosed in Reissue Patent No. 18,757, granted to Brand Beacham on May 7, 1933.

As an alternative, only the zone of the widening of the upper portion of the heel 7 may be formed with use of the three main or body yarns 16, 17 and 18, in repeating sequence, and the remainder of the stocking 1 produced from a single main or body yarn.

It is, of course, to be understood that the number of main or body yarns may be varied as desired without departure from the scope of the following claims.

Having thus described my invention, I claim:

- As a new article of manufacture, a stocking formed from a fashioned continuously-knit selvage-edged blank having progressively widened upper heel portions in which plural yarns of the same kind and count constitute successive loop

courses in repeating sequence and of which certain courses at recurrent intervals contain added end loops, and lower heel portions in which a constant number of end loops are progressively transferred inwardly.

2. A stocking according to claim 1 further characterized by having the rough or wale side of

the fabric at the inside, and by having the ridge of its rear joining seam also at the inside.

3. A stocking according to claim 1, wherein the heel portions are reinforced by a splicing yarn interknitted outward to the selvage loops formed from the other yarns.

HARRY E. KATZENMOYER.
